HAIR REWAVING DEVICE

Talmage G. Carey, St. Paul, Minn.

Application August 30, 1954, Serial No. 452,798

1 Claim. (Cl. 132—42)

This invention relates to an improved and novel hair rewaving device. It is desirable to have a device which can remove an excessively curly or kinky condition from hair, such as may result naturally or from a permanent wave, and replace it in a single operation with a soft wave of appreciable length.

It is an object therefore of this invention to provide a novel and improved hair rewaving device which can replace an excessively curled or kinky condition in hair with a soft wave of appreciable length in a single operation.

It is another object of this invention to provide a device having a member about which hair is wound under tension, and means for holding said member in a fixed position on a person's scalp.

It is a further object of this invention to provide a device for replacing a tightly curled or kinky condition in hair with a soft wave of appreciable length comprising a spindle about which hair is wound under tension and a clamping member for holding said spindle in a fixed position in relation to the hair wound thereabout.

It is more specifically an object of this invention to provide a device for rewaving tightly curled or kinky hair to produce a soft wave comprising a tubular member having a diameter of appreciable width and a member having spaced portions extending longitudinally of said tubular member adjacent opposite sides thereof, a portion connecting said spaced portions at one end and being rotatably secured to one end of said tubular member and a portion connecting said spaced portions at their other end, and means for holding said last mentioned portion in fixed position at said other end.

It is also an object of this invention to provide a device having in combination, a tubular member having a journal at one end and a plurality of diametrically aligned grooves at the other end, a clamping member having portions extending longitudinally of said tubular member at opposite sides thereof, a portion at one end of said clamping member rotatably secured on said journal and a portion at the other end of said clamping member adapted to be disposed in any of said grooves whereby said clamping member is held in locked position on said tubular member.

These and other objects and advantages of the invention will be fully set forth in the following description made in connection with the accompanying drawings in which like reference characters refer to similar parts throughout the several views and in which:

- Fig. 1 is a top plan view of applicant's device;
- Fig. 2 is a view in side elevation of applicant's device;
- Fig. 3 is a view in horizontal section taken on line 3—3 of Fig. 1, as indicated by the arrows;
- Fig. 4 is a view in elevation of one end of said device;
- Fig. 5 is a view in end elevation taken on line 5—5 of Fig. 2, as indicated by the arrows; and
- Fig. 6 is a modification of applicant's device shown in perspective with portions broken away and a portion shown in dotted lines.

2

Referring to the drawings, applicant's device is shown comprising a spindle 10. Said spindle may be formed as a cylinder or may be tubular having an appreciable diameter. In the embodiment of the invention here illustrated, said member 10 is disclosed as being tubular. Said member 10 may be formed of any suitable material, such as metal, a composition of paper or plastic. Said member 10 is here disclosed as being made of plastic material. Said member 10 has a closed end portion 10a and an open end portion 10b. Extending outwardly of said end portion 10a axially of said member 10 and tapering towards its outer end is a journal 10c. Said journal is shown as having a portion of reduced diameter at its inner end forming a groove 10d adjacent said portion 10a. Circumferentially spaced about said end portion 10b and extending longitudinally for some distance about the outer side of said member 10 are a plurality of grooves 10e. Extending diametrically across said end 10b are a plurality of grooves 10f.

20 A clamping member 11 is provided. In the embodiment of the invention here illustrated, said clamping member is disclosed as being made of a resilient and flexible plastic material. Said clamping member 11 comprises side portions 11a and 11b extending longitudinally 25 of said member 10 adjacent opposite sides thereof. Said members 11a and 11b are connected at one end by an end portion 11c having portions adapted to be disposed in any of said grooves 10f diametrically across said end 10b. Said members 11a and 11b are connected at their other end by a hub portion 11d adapted to be removably disposed over said journal 10c and rotatable thereabout axially of said member 10.

In operation, the operator will apply applicant's device to portions of a person's hair. Said hair will first be 35 prepared by having applied thereto a solution such as is commonly used with hair waving devices.

In applying applicant's device to a portion of a person's hair, said clamping member 11 will have its end portion 11c disengaged from end portion 10b of said member 10. Said clamping member is made of flexible material and is easily bent to one side of said member 10, leaving member 10 unobstructed. The operator will grasp said member 10 about its grooved end portion 10e with one hand. With the other hand the operator will 45 take a portion of a person's hair to which said solution has been applied and will wind said hair spirally about said member 10 by rotating said member as said hair is held under a considerable amount of tension. Said hair will be wound about said member 10 until said member 10 is adjacent the scalp of said person. It is also necessary that there be considerable tension on said person's hair between the scalp of said person and said member 10. Said clamping member 11 is then placed in operating position about said member 10 and having its 50 end portion 11c engaging any of the diametrically aligned grooves 10f. Said member 11 will thus be locked in position circumferentially of said member 10 and said member 10 will be held in fixed position adjacent said person's scalp.

60 It is essential that said member 10 be formed having an appreciable width so that when said person's hair is wound thereabout an excessively curly or kinky condition in said hair will be removed by being under tension about said member 10 and will be replaced by a soft wave of appreciable length formed about said member 10. It is seen that the length of said wave will be determined by the width of said member 10. The action of applicant's device also tends to remove any curly or kinky condition which may be present in the hair adjacent a person's scalp.

After a suitable length of time has elapsed, applicant's

device will be removed and a soft wave of appreciable length will be present in said person's hair replacing a previously curly or kinky condition.

A modification of applicant's device is shown in Fig. 6 in which member 10' is provided. Said member 10' is substantially identical in structure to said member 10 except that in place of said portion 10C there is provided an opening 10'C having a diameter of reduced dimension.

A clamping member 11' is provided which is substantially identical in structure to said clamping member 11 with the exception that in place of said hub portion 11D there is provided a journal 11'D. Said journal 11'D has an outer diameter of somewhat larger dimension than the diameter of said opening 10'C and having an inner portion of reduced diameter, whereby said journal 11'D is rotatably secured in said opening 10'C and is removable therefrom. In all other respects and in operation the structure shown in said Fig. 6 is the same as that previously described.

Applicant's device has been thoroughly tested in practice and has produced very satisfactory results. Applicant's device may be used with hair which has naturally a tight curled or kinky condition or with hair which has resulted in any of these conditions from a process such as permanent waving.

It will of course be understood that various changes may be made in the form, details, arrangement and pro-

portions of the parts, without departing from the scope of applicant's invention, which, generally stated, consists in a device capable of carrying out the objects above set forth, in the parts and combinations of parts disclosed and defined in the appended claim.

What is claimed is:

A hair rewaving device having in combination, a cylindrical member having a unitary imperforate surface and being of appreciable uniform diameter, the material thereof being sufficiently rigid to retain said uniformity of diameter under the tension of hair wound tightly thereabout, a hub extending outwardly of one end of said cylindrical member, a plurality of longitudinal circumferentially spaced grooves of short length about the other end portion of said cylindrical member, a plurality of diametric grooves extending across said other end of said cylindrical member, a flexible clamping member substantially rectangular in form having side portions extending longitudinally of said cylindrical member, an end portion journaled on said hub, and the other end of said clamping member being resiliently engageable with said diametric grooves.
